(57) **CLAIM**

The ornamental design for a six spoke alloy wheel, as shown and described.

DESCRIPTION

FIG. 1 shows a front perspective view of a six spoke alloy wheel;

FIG. 2 shows a front-side view of a six spoke alloy wheel; and,

FIG. 3 shows a side view of a six spoke alloy wheel shown in FIGS. 1 and 2 with the opposite side being identical as the wheel is symmetrical.
